US0D1000269S

(12) **United States Design Patent** (10) **Patent No.:** **US D1,000,269 S**
(45) **Date of Patent:** **** Oct. 3, 2023**

(54) **CLOSEABLE CONTAINER**

(71) Applicant: **Inno-Pak, LLC**, Delaware, OH (US)

(72) Inventors: **Jonathan D. Sill**, Delaware, OH (US);
Steven A. Mayer, Indianapolis, IN (US)

(73) Assignee: **Inno-Pak, LLC**, Delaware, OH (US)

(**) Term: **15 Years**

(21) Appl. No.: **29/722,938**

(22) Filed: **Feb. 3, 2020**

(57) **CLAIM**

The ornamental design for a closeable container, as shown and described.

DESCRIPTION

FIG. 1 is a perspective view of a closeable container showing a new design;

FIG. 2 is a top plan view thereof;

FIG. 3 is a front elevation view thereof, the rear being a mirror image;

FIG. 4 is a left side elevation view thereof, the right side being a mirror image;

FIG. 5 is a perspective view of the closeable container showing the closeable container in an open configuration; FIG. 6 is a perspective view of the closeable container of FIG. 1 in accordance with a second embodiment of the invention;

FIG. 7 is a top plan view thereof;

FIG. 8 is a front elevation view thereof, the rear being a mirror image;

FIG. 9 is a left side elevation view thereof, the right side being a mirror image; and,

FIG. 10 is a perspective view of the closeable container showing the closeable container in an open configuration. In the Figures, the dash-dash broken lines are for the purpose of illustrating perforations.

1 Claim, 8 Drawing Sheets
